TILT TABLE CABINET WITH HOLDING
MECHANISM

Lester Geis, New York, N. Y., and Charles L. Metzler, Palisades Park, N. J., assignors to American Optical Company, Southbridge, Mass., a voluntary association of Massachusetts

Application July 12, 1946, Serial No. 683,026

9 Claims. (Cl. 312—155)

1

This invention relates to cabinets and like devices and more particularly to mechanisms for use therewith for allowing and controlling the tilting of such a cabinet in a vertical plane relative to a pedestal or base supporting said cabinet.

It is often desirable to arrange a relatively large cabinet, such as might be used for housing a microfilm projector-reader as shown by our prior Design Patent No. 143,967, an optical comparator or the like, upon a mobile or portable base and to provide such cabinet and base with suitable mechanism so that the cabinet may be easily and readily tilted and locked in any one of a plurality of positions convenient to a person operating or using the cabinet, or so that a projector thereon may be properly positioned for projection purposes.

It is, accordingly, an object of the invention to provide a cabinet upon a suitable supporting pedestal or base in such a manner that it may be tilted relative thereto and to provide suitable mechanism for controlling the tilting and locking of said cabinet relative to the base.

It is also an object of the invention to provide for a cabinet and a base a mechanism for controlling tilting of the cabinet and with the mechanism so arranged that it is for the greater part completely enclosed within said cabinet and base.

A further important object of the invention is to provide for a device of the character described a mechanism including a foot lever which may be conveniently operated by the operator and which mechanism includes means for positively and automatically locking the tiltable cabinet in any one of a plurality of predetermined positions when the pressure on the foot lever is released.

A further object of the invention is to provide as part of such a control mechanism additional means which is associated with the tiltable cabinet and base and which may be adjusted so as to provide a proper resistance or drag to the tilting action of the cabinet when the locking means therefor is in a released position, such drag means preventing free or uncontrolled tilting of the cabinet but allowing the user thereof to readily tilt the cabinet as desired when the locking means is released.

Other objects and advantages of the invention will become apparent from the detailed description which follows taken in conjunction with the accompanying drawings in which:

Fig. 1 is a side elevational view of a projector-reader comprising a portable base, a tiltable cabi-

net supported thereby and new and improved mechanism for controlling the tilting and locking thereof;

Fig. 2 is a longitudinal sectional view, on an enlarged scale, of a lower portion of the structure of Fig. 1;

Fig. 3 is a transverse sectional view taken substantially on line 3—3 of Fig. 2 and looking in the direction of the arrows;

Fig. 4 is a transverse sectional view taken substantially on line 4—4 of Fig. 2 and looking in the direction of the arrows; and

Fig. 5 is a detailed sectional view taken substantially along line 5—5 of Fig. 2 and looking in the direction of the arrows.

Referring to the drawings in detail and particularly to Fig. 1 it will be seen that the projector-reader or similar device indicated by the numeral 18 comprises a portable base or pedestal 12 and an enclosure or cabinet 14 which is provided with an opening 15 in the bottom portion thereof for receiving the upper end of said pedestal. The cabinet is arranged to tilt about a transverse axis 16 to various predetermined positions of adjustment, certain of which are indicated by dotted lines 18 and 20 (see Fig. 2). The base 12 is of substantial length and width and has an upwardly extending hollow central portion 22 which is formed by a front wall 24, a rear wall 26 and side walls 27 and 28. At the upper front corners of this hollow portion 22 are provided a pair of integral bearings 30 which are transversely aligned and concentric with the axis 16 about which the cabinet 14 tilts. Stub shafts 32 and 34 are positioned in the bearings 30 and locked in place therein by set screws 35 and free end portions 32' and 34' of said shafts extend outwardly from bearings 30 so as to form pivotal supports for apertured brackets 36 and 37 which are welded or otherwise fixedly secured to a transversely extended frame member 38 which is in turn arranged as a main supporting member for and within the cabinet structure 14.

Since the weight of the cabinet 14 and associated structure supported by shafts 32 and 34 may be considerable, it is desirable to provide suitable mechanism for allowing and controlling the tilting action of the cabinet relative to the base. This control mechanism is made of a rigid and sturdy construction and comprises a friction or drag mechanism for resisting free tilting action of the cabinet as well as a locking mechanism for positively preventing tilting action thereof except when it is rendered inoperative or ineffective by the user of the device. The locking mechanism is

indicated by the numeral 40 and the drag mechanism is indicated by numeral 42. The locking mechanism comprises, in the present preferred construction, an actuating member 44 arranged in the form of an elongated bent lever having an operating arm 46 extending outwardly through an opening 48 in the front wall 24 of the hollow portion 22 so as to provide a treadle 50 which may be depressed by the foot of the user of the device for rendering the locking mechanism temporarily ineffective when it is desired to tilt the cabinet. The actuating lever 44 is also provided with an upwardly extending arm 52 and this arm has a hooked upper end portion 54 which is adapted to engage suitable holding means such as any one of a series of slots 56 formed in a forwardly extending flange 58 of a bracket 60 which has a second flange 62 thereof welded or otherwise secured to the rear wall of the cabinet 14.

When desired, the operator may grip an upper part of the cabinet 14 while depressing the treadle 50 and by exerting a forward or rearward pressure thereon tilt the cabinet about axis 16. The hooked end portion 54 is at such time disengaged from the slots 56 and the cabinet may be tilted to any one of a plurality of predetermined positions, which in the construction disclosed would be to the extreme positions of tilt indicated by dotted lines 18 and 20 or to positions intermediate thereof. Obviously, the number of positions and the range of tilting shown could be varied considerably if desired without requiring any material change in the structure. A projection 64 on a lower portion of the bracket 60 extends forwardly sufficiently to be engaged by the hooked end portion of lever 44 when disengaged from slots 56 and thus serve to limit the extent of forward tilting of the cabinet. An equivalent projection 66 is provided at the upper end of bracket 60 and serves to limit, in a similar manner, rearward tilting of the cabinet.

The bent intermediate portion of lever 44 is secured, preferably by welding, to a pair of angle plates 68 (see Fig. 4) which are apertured to receive a rod or pivot pin 70 and positioned about this rod in spaced relation at opposite sides of the plates 68 are a pair of tubular spacers 72 which may likewise be rigidly secured, as by welding, to plates 68 and thus center the lever 44 and form a sturdy supporting structure for this lever. The pin or rod 70 is removably held in the position shown by Fig. 4 by a cotter pin or the like 73. The ends of pin 70 are positioned in openings 74 in the side walls 27 and 28 so that the pivoting action of lever 44 may take place in these openings 74.

The hooked upper end portion of lever 44 is urged toward locking engagement with the slots 56 in bracket 60 by a pair of tensioned springs 76 (see Fig. 3) which have their lower ends engaging in holes drilled in the arm 46 and their upper ends engaging projections 78 and 79 carried by stub shafts 32 and 34 respectively. Projection 79 is preferably formed integrally with stub shaft 34. In the construction disclosed, however, where sufficient room must be allowed for the insertion of stub shaft 32 after stub shaft 34 and integral projection 79 have been inserted, stub shaft 32 is formed in a slightly different way. The projection 78 is detachable from shaft 32 and the stub shaft 32 is provided with an axially threaded opening at its inner end for receiving a threaded end portion 82 of this removable projection 78. After shaft 32 has been positioned to extend through bearing 30 and bracket 36, pro-

jection 78 may be screwed into place in said threaded opening and thus serve to support the upper end of one of the springs 76. It should be observed here, however, that if desired, a single spring 76 may be employed fairly satisfactorily in which case projection 78 need not be employed on stub shaft 32.

The friction mechanism 42 mentioned previously comprises an integral upstanding projection 84 (see Fig. 2) which is provided upon the upper edge of the rear wall 26 and this projection is provided with a transverse opening therethrough for receiving a pivot supporting member 86 which may be retained therein in any convenient manner and to which is pivotally secured by bolt 87 the lower end of a link 88. This link has its other end pivotally connected to a second link 90 which is in turn pivotally connected at its opposite end to a block 92 bolted or otherwise secured to an upper portion of the flange 58. The adjacent enlarged ends of links 88 and 90 are secured together by a friction clutch or drag mechanism 94 which, as shown best by Fig. 5, comprises an apertured plate 96 having a projecting finger 97 arranged to engage between a pair of straight fingers 98 carried by link 90 so that the relative position of members 90 and 96 will be at all times maintained. Between plate 96 and the enlarged end of plate 90 are clamped, by a bolt 99 and a nut 100 adjustably positioned thereon, the enlarged end portion of link 88 and a friction disc 102, preferably formed of fibrous material, so that this disc and proper adjustment of nut 100 may be utilized to provide sufficient frictional resistance or drag between links 88 and 90 to prevent free tilting of the cabinet 14 when brake lever 44 is disengaged. Proper adjustment of the linkage, however, will allow the operator of the device to tilt the cabinet about axis 16 to different positions of adjustment whenever desired while treadle 50 is being depressed. A lock washer 103 may be used as shown, if desired, for preventing loosening of nut 100 and a squared portion 104 of bolt 99 in a squared opening in link 90 precludes rotation of the bolt relative thereto.

The slot 48 in the front wall 24 of the hollow column 22 is formed so that its lower edge 105 serves as a positive stop for limiting the downward movement of the lever 44. When this lever is in engagement with stop 105, its hooked end 54 will be disengaged from slots 56 but positioned so as to be in the path of movement of the projections 64 and 66 and thus serve to limit the tilting movement of the cabinet 14 in either direction.

Having described our invention in detail what we claim is as follows:

1. The combination of a base, a cabinet, pivot means supporting said cabinet for tilting movement relative to said base, and mechanism for controlling the tilting movement of said cabinet, said mechanism being located principally within said base and cabinet and comprising a fixed member having holding means secured relative to said cabinet, a readily operable exposed arm movably carried on said base and carrying complementary holding means engageable with said holding means on said fixed member, and spring means for normally urging said complementary holding means into engagement with said holding means for releasably locking said cabinet in any one of a plurality of predetermined positions of adjustment.
2. The combination of a base, a cabinet, pivot

means supporting said cabinet for tilting movement relative to said base, and mechanism for controlling the tilting movement of said cabinet, said mechanism being located principally within said base and cabinet and comprising a fixed member having holding means secured relative to said cabinet, a pivoted member movably carried on said base and comprising a readily operable exposed actuating arm and a restraining arm engageable with the holding means on said fixed member, and spring means for normally urging said restraining arm into engagement with said holding means for releasably locking said cabinet in any one of a plurality of predetermined positions of adjustment.

3. The combination of a base, a cabinet, pivot means supporting said cabinet for tilting movement relative to said base, and mechanism for controlling the tilting movement of said cabinet, said mechanism being located principally within said base and cabinet and comprising a fixed member having holding means secured relative to said cabinet, a pivoted member movably carried on said base and comprising a readily operable exposed actuating arm and a restraining arm engageable with the holding means on said fixed member, spring means for normally urging said restraining arm into engagement with said holding means for releasably locking said cabinet in any one of a plurality of predetermined positions of adjustment, and means connected to the interior of said cabinet and said base and adjustable to provide a predetermined amount of resistance or drag to tilting movement of said cabinet relative to said base.

4. The combination of a hollow base, a cabinet carried thereby, said hollow base extending into an opening in the bottom of said cabinet, pivot means enclosed within said cabinet and base and serving to support said cabinet for tilting movement relative to said base, and mechanism the greater portion of which is enclosed by said cabinet and base for controlling the tilting movement of said cabinet, said mechanism comprising a fixed member on said cabinet, a readily operable member movably carried on said base and comprising an actuating arm extending outwardly of said base and a restraining arm engageable with said fixed member, and spring means normally urging said restraining arm portion into engagement with said fixed member for releasably locking said cabinet in any one of a plurality of predetermined positions of adjustment.

5. The combination of a hollow base, a cabinet carried thereby, said hollow base extending into an opening in the bottom of said cabinet, pivot means enclosed within said cabinet and base and serving to support said cabinet for tilting movement relative to said base, and mechanism the greater portion of which is enclosed by said cabinet and base for controlling the tilting movement of said cabinet, said mechanism comprising a fixed member on said cabinet, a readily operable member movably carried on said base and comprising an actuating arm extending outwardly of said base and a restraining arm engageable with said fixed member, and spring means normally urging said restraining arm portion into engagement with said fixed member for releasably locking said cabinet in any one of a plurality of predetermined positions of adjustment, and means operatively connected to said cabinet and base and adjustable to provide a predetermined amount of resistance or drag to

tilting movement of said cabinet relative to said base.

6. The combination of a hollow base, a cabinet, pivot means supporting said cabinet for tilting movement relative to said base, and mechanism for controlling the tilting movement of said cabinet, said mechanism being located principally within said base and cabinet and comprising locking means and adjustable friction means, said locking means comprising a fixed member having a plurality of slots secured relative to said cabinet, a readily operable latch movably carried on said base and selectively engageable with any one of the slots in said fixed member, an operator controllable arm for actuating said latch extending outwardly of said base and spring means normally urging said latch into engagement with said slots for releasably locking said cabinet in any one of a plurality of predetermined positions of adjustment, said friction means being connected to said cabinet and said base and adjustable to provide a desired amount of frictional resistance to tilting movement of said cabinet relative to said base.

7. The combination of a base, a cabinet, pivot means supporting said cabinet for tilting movement relative to said base, and mechanism for controlling the tilting movement of said cabinet, said mechanism comprising locking means and adjustable friction means, said locking means comprising a fixed member on said cabinet, a readily operable member movably carried on said base and engageable with said fixed member for preventing relative movement between said cabinet and base, and spring means normally urging said member into engagement with said fixed member for releasably locking said cabinet in any one of a plurality of predetermined positions of adjustment, said friction means comprising a pair of interconnected links connected respectively to said cabinet and base and an adjustable connection between said links arranged to provide an adjustable frictional resistance of amount suitable to prevent free tilting movement of said cabinet relative to said base.

8. In a device of the character described the combination of a hollow base, a cabinet carried thereby, said hollow base extending into an opening in the bottom of said cabinet, pivot means enclosed within said cabinet and base and serving to support said cabinet for tilting movement relative to said base, and mechanism partially enclosed within said cabinet and base for controlling the tilting movement of said cabinet, said mechanism comprising locking means and adjustable friction means, said locking means including a fixed member on said cabinet, a readily operable member movably carried on said base and having an actuating arm extending outwardly through an opening in said base for convenient operation by the foot of the user of the device and a restraining arm engageable with said fixed member, and spring means normally urging said restraining arm into engagement with said fixed member for releasably locking said cabinet in any one of a plurality of predetermined positions of adjustment, said friction means being connected to said cabinet and base and adjustable to provide a frictional resistance suitable to prevent free tilting movement of said cabinet relative to said base when said restraining arm is released from said fixed member.

9. In a device of the character described the combination of a hollow base, a cabinet carried thereby, said hollow base extending into an open-

ing in the bottom of said cabinet, pivot means enclosed within said cabinet and base and serving to support said cabinet for tilting movement relative to said base, and mechanism for the greater part enclosed within said cabinet and base for controlling the tilting movement of said cabinet, said mechanism comprising locking means and adjustable friction means, said locking means including a fixed member on said cabinet, a readily operable member movable carried on said base and having an actuating arm extending outwardly through an opening in said base for convenient operation by the foot of the user of the device and a restraining arm engageable with said fixed member, and spring means normally urging said restraining arm into engagement with said fixed member for releasably locking said cabinet in any one of a plurality of predetermined positions of adjustment, said friction means comprising a pair of interconnected links connected respectively to said

5 cabinet and base and an adjustable connection between said links arranged to provide an adjustable frictional resistance or drag suitable to prevent free tilting movement of said cabinet relative to said base when said restraining arm is released from locking engagement with said fixed member.
